Patented Dec. 6, 1921.

INVENTOR:

Henry F. Corder,
BY John Elias Jones, ^{ATTORNEY.}

ATTORNEY.

UNITED STATES PATENT OFFICE.

HENRY F. CORDES, OF CINCINNATI, OHIO.

DOOR-HOLDER.

1,399,467.

Specification of Letters Patent.

Patented Dec. 6, 1921.

Application filed August 13, 1920. Serial No. 403,309.

To all whom it may concern:

Be it known that I, HENRY F. CORDES, a citizen of the United States of America, and a resident of Cincinnati, in the county of 5 Hamilton and State of Ohio, have invented a certain new and useful Improvement in Door-Holders, of which the following is a specification.

This invention relates to extensible-holders for doors that are adapted to lock said doors closed or shut from the inside, or to maintain and brace them in rigid place or position when open at the desired angle from the opening in the building which it is 10 designed to fill when closed, and the main object of the invention is to provide each door with a pair of longitudinally sliding or telescopic bars, one of which bars has holes pierced at intervals apart therein and the 15 other bar of which has a latch-pin that is adapted to engage the respective holes in said first bar to set and securely hold the device in a locked condition when the door is fully closed or when at the angle that the door is 20 intended to assume when half-way open or beyond half-way open, or to assume any desired angle less than half-way open position, for purposes other than that of permitting 25 vehicles to freely pass into and from the building, especially for automobile use.

The invention consists of the combination of longitudinally-extensible telescopic parts or bar-members, one member having a longitudinal series of holes therein and 30 the other having a latch-pin pivotally-mounted thereon and adapted to respectively engage the said holes in the first-named member to suit the distance the door shall assume from normally-closed position when extended 35 into open use, and the said telescopic members being each pivotally-mounted at their extreme opposite ends when assembled in sliding relation for attachment to the building and to the door that is to be kept 40 closed or to be angled or held in open position from the door-way or opening for the entrance and exit of an automobile or other vehicle that is housed in the building.

In the accompanying sheet of drawings, 45 which serve to illustrate my invention herein—

Figure 1 is a perspective view of the preferred form of device embodying my invention, showing it detached from using-place 50 and in extended position to allow for angling and checking the door just beyond half-way

open; Fig. 2, a plan view, showing my device in position for holding or checking the door half-way open, a fragment of the doorway of the building being in cross-section; 60 Fig. 3, a view similar to Fig. 2, but of a modified form that has an auxiliary or compensating arm which is adapted to hold or check the door practically all the way open; Fig. 4, a detail of the spring-latch pin for 65 detachably locking or coupling the two members of the device in both closed and open positions of the door; Fig. 5, a transverse section of the pair of sliding or telescopic bars, taken on the dotted-line 5, 5, of Fig. 2; 70 and Fig. 6, a vertical section taken on the dotted-line 6^a, 6^a, of Fig. 2, showing the pair of telescopic bars and the coupling-bracket-arm that is mounted on a sectional fragment of the door. 75

6 indicates a bar having a longitudinal series of holes 7 pierced therein, at suitable intervals apart, and 8, a companion bar having right-angled flanges 9, 9, inwardly-turned along its opposite edges and adapted to slidingly-receive the bar 6 for longitudinal telescopic-engagement. These bars 6 and 8, in use, lie with their broad flat faces horizontal and for the purpose of bracing utility and strength, as well as the desired rigidity, 85 as hereinbefore and hereinafter noted.

10 indicates each one of a pair of L-shape plates, with their horizontal portions in contact and their vertical portions pierced with holes 11 adapted to receive screws or 90 the like 12 for fastening them in position on the face of the upright 13 of the door-frame in the entrance to a building wherein a vehicle is to be kept ready for use.

14 indicates each one of a pair of horizontal bars extending, duly spaced apart, from the pair of contacting horizontal portions of the bracket comprising the L-shape plates 10, and having vertical securing-bolts 15, the latter being adapted to engage holes 100 16, arranged in transverse pairs in the said horizontal portions of the said bracket, at three intervals apart to adapt the bars 14 to be set nearer the upright 13 or farther away from it to suit the thickness of door (designated A), thus making the connection an adjustable one between the bars 14 and the bracket-bars 10. 105

The outer end of the perforated bar 6 is pivotally-connected to the outer spaced ends 110 of the bracket-bars 14 by means of a vertical bolt 17, a vertical stop-pin 18 being set

- upright in the upper face of the bar 6 near said outer end to limit the extended, outward, pivotal movement of the said bar 6 in the swinging open of the door.
- 5 The outer or tail end of the channeled bar 8 is fastened by means of a vertical rivet 19 within a U-shape arm 20 extending outwardly from vertical flanges or feet 21 that are secured to the inner face of the door by
- 10 means of horizontal bolts or screws 22, as best seen in Fig. 6. It will be seen in said Fig. 6 that the inner head of the rivet 19 lies flush with the inner face of the upper member of the U-shape arm 20 so that the
- 15 free sliding of the bar 6 in the channeled bar 8 is not hindered.

23 indicates a vertical latch-pin mounted in a hook-shape holder 24 which is pivotally-hinged at 25 to the inner end of the

20 channeled bar 8, as best seen in Fig. 4, and having an upright right-angled extension 26 made in its hinge-eye portion for engagement with a spring 27 whose rear end is secured to the upper face of the channeled bar 8 by

25 means of one or more rivets 28.

The latch-pin 23 is tapered at its lower portion for facilitating its engagement with the several holes 7 in the bar 6 and its upper portion is of uniform diameter so as to frictionally and closely fit within said openings or holes 7 when in using position, to rigidly or securely lock and hold the door when either open or closed. The spring 27 is intended to exert its pressure on the right-angled extension 26 of the latch-pin hinge to prevent accidental disengagement of the latch-pin from within the hole 7 in which it may be lodged.

The upturned hook end of the latch-pin 40 forms a handle by which to conveniently and positively manipulate it, but the pin itself can be readily released from any of the holes 7 by simply pressing upwardly with the thumb or hand on its lower end

45 which is extended to some extent somewhat below the bottom face of the bar 6.

In operation, the device is used in duplicate in a double door-way, wherein folding doors are employed to close a broad opening 50 adapted to the entrance and exit of a vehicle, such, more especially, in this instance, as an automobile housed in a garage or like building. The duplication of the device is in the employment of one complete telescopic set 55 of bars 6 and 8 on each of the two doors, placed or mounted on the inner face thereof, a little above waist high for the best results and greatest convenience. When the doors are shut or closed, the bar 6 is in

60 complete closed condition within the channeled bar 8, the inner end of the latter lying near the outer ends of the bracket-bars 14, with the hook-end of the latch-pin 23 just within approaching contact with the

65 said outer ends of the bracket-bars 14, and

with the latch-pin in engagement with the first hole 7 of the longitudinal series in the bar 6, thereby locking the door when in said shut or closed condition, assuming that there is another ordinary door-way or entrance for the user.

When it is desired to open the door, the latch-pin is released from the said first hole 7 and the outward swinging of said door causes the bar 6 to turn on its hinge-connection with the bracket-bars 14 until it reaches the angle seen in Fig. 2, whereby the door itself is placed at a right-angle to the door-way, the channeled bar 8 in the meantime sliding along the bar 6 that 80 swings with it, and both bars 6 and 8, together with the U-shape arm 20 and the bracket-bars 14 making a very powerful brace to check and prevent the door from swinging away from or losing its open position, and keeping the said door at the desired angle for the free entrance and exit, as hereinbefore stated, of the vehicle through the door-way.

It will be observed that there is a sufficient number of holes 7 in the bar 6 to provide for angling the door at a distance somewhat beyond that shown in Fig. 2, as well as within the right-angled position to suit the purposes of the user, as he may wish 95 to leave the doors but partly open for ventilation, or for light, or for his easy entrance to and fro, when the passage does not need to be quite so wide as for an automobile or other vehicle.

To set the door at an angle somewhat beyond the right-angled one seen in Fig. 2, especially when it is desired for any reason to have it all the way open, I provide an auxiliary filler or compensating bar 29, shown 105 in Fig. 3, that lies between the inner end of the bar 6 and the outer ends of the pair of bracket-bars 14 that project from the bracket proper 10. This filler-bar provides allowance that is required for the outward swinging of the pair of telescopic bars when in sliding-engagement with each other and, also, for the tail-end 30 of the bar 6 toward the inner face of the door. In other words, the said filler-bar forms a compensating device for the swinging backward of the door 110 toward the building, beyond the right-angle or ninety (90) degree position seen in Fig. 2.

Stop-pins 18 and 31 are used on the bar 6 and the said filler-bar 29, respectively, to 120 limit the movements of both of those bars in the hinging thereof when arranging or setting the door at the desired angle, and, also, when closed.

In Fig. 3 it will be seen (in dotted-lines) 125 that the inner end 34 of the bar 6 is sloped or beveled, and that a pair of shouldered jaw-plates 35 extends from the squared outer end 36 (shown dotted) of the filler-bar 29. The inner beveled end 34 is pivot-

ally-connected in the jaw-plates 35 by means of a bolt 37. In operation, the door, when swung outwardly, (after the latch-pin has been released from bar 6), draws with it in 5 a curved path the filler-bar 29 until the stop 31 abuts the edge of the bracket-bars 14 and said filler-bar 29 assumes a right-angle to said bracket-bars 14, the beveled end 34 of bar 6 then contacting with the square end 36 of said filler-bar, and then the further 10 swinging of the door to full open position causes the said sloped end 34 to pass from said square end 36 until the stop 18 on the bar 6 abuts the edge of the shouldered part 15 38 of the jaw-plates 35. In closing the door the sloped end 34 first contacts with the square end 36 and then the filler-bar 29 follows, to duly hinge or pivot on the bolt 17 until in alinement with the bracket-bars 14.

20 The series of holes 7 need not extend the entire length of the bar 6, as there would be no angle beyond the last hole 7 seen in dotted-lines in Figs. 2 and 3, to which the door could reasonably be placed for any ordinary use, but I provide a few holes 32 at the tail-end 30 of the bar 6 in Fig. 3, as well as in the bar 6 of Fig. 2, and adapt them to receive an ordinary pin, nail, or the like 33, convenient, when it is desired to 25 quickly set the two bars 6 and 8 in locking-relation by means of the latch-pin which can be readily inserted in the desired hole 7, especially in the dark, or in a faint light, or when in haste, and without fumbling about 30 35 aimlessly, or at random, for the desired hole in the said bar 6, which would otherwise ensue under excitement, with the wind blowing or other undue pressure on the door, causing it to totter and shake on its hinges.

40 The pin 33 used in either of the tail-holes 32 in the bar 6 is shown in Figs. 2 and 3 as being in contact with the end of the channeled bar 8 for action.

I claim:—

45 1. A door-holder comprising a pair of telescopically-sliding elongated bar-members, one bar-member being channeled and the other being plain the plain bar having a longitudinal series of holes or perforations 50 pierced therein, a horizontal forked-bracket extending outwardly from the upright side-frame of the door-way and to the outer end of which forked-bracket one end of the said

pierced plain bar is pivotally connected, an upright pin extending from the upper face 55 of the said plain bar near its pivotally-connected end and adapted to form a stop in connection with said forked-bracket to limit any further backward-movement of the said plain bar toward the door, a horizontal U- 60 shape bracket-arm extending from the inner face of the door and to which said channeled-bar is pivotally connected at its outer end and serves as a take-up or compensating pivotal-coupling between the channeled-bar 65 and the inner face of the door, and a pointed latch-pin mounted on a handle-bar that is hinged to the inner end of the channeled-bar and adapted to engage the respective holes in the plain bar for holding the door in 70 open position at the desired angle from the door-way, or for otherwise locking the door when shut or entirely closed within said door-way, substantially as shown and described.

75 2. A door-holder comprising a pair of longitudinally-telescoping bars, one a channeled-bar and the other a plain-bar, a series of holes pierced in said plain-bar, a horizontal forked bracket-bar extending outwardly from and adjustably-mounted on the side-frame of the door-way, a horizontal auxiliary link or filler-bar pivotally-connected at one end to the said forked bracket-bar and having pivotal-connection at its 80 other end to the said plain-bar, an upright pin or stop provided on the said auxiliary link or filler-bar adjacent the outer end of said bracket-arm, an upright pin or stop on the said plain-bar adjacent the outer end of 85 said link, a horizontal forked or U-shape bracket-arm extending from the inner face of the door and pivotally-connected to one end of the channel-bar, a vertical tapered or pointed latch-pin having a hook-shape 90 handle and pivotally-connected to the inner end of the channeled-bar, and having, also, an upright right-angled arm or rest the latter extending from its hinge-end, and a spring-arm connected at one end to the channeled-bar and adapted to elastically rest and press upon the said upright right-angled arm on the latch-pin handle, substantially 95 as shown and described.

HENRY F. CORDES.
